Thomas Mitchell

UNITED STATES PATENT OFFICE.

THOMAS MITCHELL, OF ALBANY, NEW YORK.

IMPROVEMENT IN STEAM-GENERATORS.

Specification forming part of Letters Patent No. 59,051, dated October 23, 1866.

To all whom it may concern:

Be it known that I, THOMAS MITCHELL, of Albany, in the county of Albany and State of New York, have invented a new and Improved Machine for Generating Steam, to take the place of steam-boilers; and I do hereby declare that the following is a full, clear, and exact description of the same, reference being had to the annexed drawings, making a part of this specification.

Figure 1 is an outside view of the steam-chamber. Fig. 2 is the water-tank. Fig. 3 is the pressure-valve.

Similar letters of reference indicate corresponding parts in the several figures.

This invention consists in the use of a steam tank or chamber, a water - tank, a pressure-valve, a force-pump, connecting-pipes, valves, cocks, expansion-rods, and damper-doors, so made and connected that water is let into the steam-chamber when heated to the degree required, so that any given number of pounds of steam may be made instantaneous, and the quantity of water let in and graduated by the pressure of steam in the chamber.

This invention secures three important advantages in regard to steam - power—first, perfect safety against boiler-explosions; second, a saving of at least one-half the amount of fuel; and, thirdly, about three - fourths of the bulk, weight, and cost of steam-boilers, substantially as hereinafter described.

Letter A of Fig. 1 is a flue, on top of which the smoke-stack is placed, answering the purposes of a brace for the head and crown-sheet of the chamber, increasing the steam-surface, and a draft from the furnace.

Letter B is a water-distributer, made guttering and with an inclination downward from the flue, receiving the water from the pipe C, conducting a part of it to the walls of the chamber, and letting a part fall from the short gutters midway on the crown-sheet below.

Letters D D are damper-doors, which serve the purposes of covering the draft - openings when down and shutting off the draft from the center flue when up, and also the all-important one of covering and protecting the crown-sheet from being heated too hot. These doors are moved by the expansion-rods G G, one end of each of which is fastened firmly in each side of the chamber, and the other loose, so that

when the degree of heat under the crown-sheet is obtained sufficiently high to evaporate the water let into the chamber immediately into the steam, and yet not so high as to injure the crown-sheet, at exactly this point these rods have expanded to such a length that they raise the dampers covering the crown-sheet, and also covering completely the flue, shutting off the draft from the chimney, and opening the doors in the sides of the chamber, giving a clear space for the cold air to pass through.

E is the lever (and which may be doubled to give a quicker motion) by which the doors are moved by the expansion-rods.

Fig. 2 is the water-tank, letter A of which is the pipe leading from a force-pump, through which the water is forced into the tank, keeping up a pressure in it high enough to feed the chamber against any given pressure of steam. Letter B is the cock on the connecting-pipe between the water-tank and the steam-chamber, on which is a gear-wheel, and moved by the gear-rack, connected with the lever C. This lever may also be doubled to give a quick motion to the cock.

Fig. 3 is the pressure-valve. Letters A A is the pipe leading from the steam - chamber into it, and thus always keeping the pressure in the valve and the chamber equal. There is rubber packing fastened between two flanges, represented by the one under the dome on this valve, the full size of the flange separating the steam below the flange from the clear space above it under the dome. B is the stem rising up through the center of the valve, on the lower end of which is a flat washer, resting on the top of the packing. C is a lever resting on the top of this stem or fulcrum. On the upper end of this lever is the gear-rack already described.

It is clear from this that, the pressure being equal in the chamber and in this valve, the stem will rise and fall by the steam's rising or falling, when it falls, which it will do, by exhausting any amount of steam from the chamber, and this fall will let the lever C fall also, which turns the cock on the connecting-pipe between the steam-chamber and the water-tank, and therefore turning the cock, and thus letting just water enough into the chamber, which is instantaneously evaporated into

steam to make up the quantity of steam thus exhausted, and which again instantly raises the stem in the pressure-valve, and thus again shutting off the water from the tank, and keeping it shut off until more steam is used by the running of the engine or otherwise; and this action is continued as long as the fire is kept up in the furnace and the force-pump is kept in motion.

Letter D of Fig. 2 is a water-valve for the purpose of letting the water off when the pressure is greater than requisite to feed the steam-chamber, and which is again conducted back into the reservoir by the pipe E E, if required, for further use.

Letter F is the beam, containing figures and niches, on any one of which the pea may be placed, giving the pressure required to feed the chamber against any given number of pounds of steam. If sixty pounds is wanted, then set the pea on sixty-five pounds on the water-valve and sixty on the beam connected with the pressure-valve. In the same manner they are to be set to give any number of pounds of steam required.

The mode of operation is as follows: First, fire is made in the fire-box, when there is no water in the steam-chamber, until the heat reaches that degree under the crown - sheet which lifts the damper-doors, at which point water is forced by hand with the force-pump, (detaching it from the engine for this purpose.)

This is continued until the amount of steam required is obtained. When this is done, the pump is again attached to the engine, and the steam being let onto it, as in ordinary cases, continues the action as long as is required.

It will be seen by this invention that it is impossible for either water to accumulate in the chamber, or the crown-sheet be injured by any amount of fire it is possible to make in the furnace.

It will also be seen that by putting fire-brick in the fire-box the fire cannot come in contact with the shell of the steam - chamber, which is indeed nothing but a single ordinary plate of boiler-iron.

It will also be seen this machine is a most perfect water and steam gage.

Having thus described my invention, what I claim as new, and desire to secure by Letters Patent, is—

The combination of the means, substantially as herein described, for generating the steam, with the means, substantially as herein described, for controlling the introduction of the water into the generator by the pressure of steam generated, as and for the purpose set forth.

THOS. MITCHELL.
